UNITED STATES PATENT OFFICE

169,888

WALL AND TOWER UNIT FOR A TOY FORTRESS OR SIMILAR ARTICLE

Gerhard R. Beyer, Conway, N. H.

Application February 2, 1951, Serial No. 14,078

Term of patent 7 years

(Cl. D34—15)

To all whom it may concern:

Be it known that I, Gerhard R. Beyer, a citizen of the United States, residing at Conway, county of Carroll, and State of New Hampshire, have invented a new, original, and ornamental Design for a Wall and Tower Unit for a Toy Fortress or Similar Article, of which the following is a specification, reference being had to the accompanying drawing, forming a part hereof.

The figure in the drawing is a perspective view of a wall and tower unit for a toy fortress or similar article showing my new design. The back of the wall and tower unit has substantially the same ornamental appearance as the front.

I claim:

The ornamental design for a wall and tower unit for a toy fortress or similar article, as shown and described.

GERHARD R. BEYER.
